Attorney

UNITED STATES PATENT OFFICE.

CHARLES P. TRIMBLE, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

PNEUMATIC CLAMPING TOOL.

Application filed June 5, 1925. Serial No. 35,105.

This invention relates to a pneumatic clamping tool and comprises a body, a piston cylinder and a valve chamber in the body, a piston in the cylinder and a manually operated valve in the chamber, clamping jaws on one end of the body, connections between the piston and one of the clamping jaws for operating the latter and a handle on the other end of the body; all as more fully hereinafter set forth and as claimed.

In certain arts as, for instance, in the manufacture of covered cushion seats or the like in which the cover extends around a bottom border frame and is held in place by a metallic clamp or the like, it has always been necessary to attach the clamps by use of a manually operated tool, such as a pair of specially constructed pliers, or by hammering the clamps in place. Among other objects of this invention is the provision of a pneumatic tool which is adapted for attaching these cover holding means in place conveniently and cheaply. By the device to be described, the clamps are easily and securely squeezed into place and by keeping the clamping jaws of the tool in closed position, the operator can work from one end to the other of a long clamp. This is a particularly useful feature as long clamps are not generally used because of the difficulty of attaching them by the methods now in use.

In the drawings I have shown one form of a specific embodiment of the invention.

Fig. 1 is a longitudinal vertical section partly in elevation through the complete tool;

Fig. 2 is an enlarged fragmentary section of the upper portion of Fig. 1;

Fig. 3 is a section along line 3-3 of Fig. 2;

Fig. 4 is an enlarged perspective view of the valve stem;

Fig. 5 is a plan view of the bumper plate;

Fig. 6 is a plan view of the movable clamping jaw.

In the drawings 1 indicates the body of the tool, preferably of aluminum or the like. Formed in the lower portion of the body is a piston cylinder 2 open at one end and arranged in the cylinder is a piston 3 mounted upon piston rod 4 and provided with leather packing 5 held in place by disk or washer 6 and nut 7. Secured around the rod 4 is

spiral spring 8. Cylinder head 9 is screwed into the open end of the cylinder 2 and spring 8 causes the nut 7 to abut against the cylinder head. One end of the piston rod 4 extends slidably through bushing 10 which may be screwed or pressed into the closed end of cylinder 2. Oil conduit 11 is provided through the body on bushing 10 for lubricating piston rod 4. Bumper plate 12 is conveniently attached to the body by means of screws, rivets or the like (not shown). Clamping jaw 13 is mounted at a point between its ends on the bumper plate 12 by means of hinge pin 14 passing through the lugs 15 on the bumper plate. One end of the clamping jaw 13 is provided with a shaped portion 16 of such a form as may be suitable for the work desired. The other end of the clamping jaw is cut away to form a substantially U-shaped yoke 17 near the ends of which are formed vertical slots 18. The yoke 17 is connected to piston rod 4 by hinge pin 19 passing through slots 18 and through one end of the piston rod 4. Hinge pins 14 and 19 are provided with suitable cotter pins or the like (not shown) for holding them in place. Suitable washers may be used in making the pivotal connections described. Mounted upon the cylinder head 9 by means of screws or the like is handle 20 adapted to be grasped by the operator. If desired the cylinder 2 may be provided with sleeve bushing 21 of brass or other friction metal.

The upper portion of the body 1 is provided with valve chamber 22 having an air inlet nipple 23 and valve stem 24. Valve stem 24 is provided at one end with a valve head 25 adapted to seat on bushing 26 to make an air tight joint therewith. Upon the other end of the valve stem is provided thumb button 27 suitably beveled as at 28 so as to register with beveled edge 29 of bushing 30 to make an air tight joint when edges 28 and 29 contact. Coiled spring 31 is provided around the thumb nut for keeping the valve normally in closed position with valve head 25 seated on bushing 26. The lower side of the central portion of the valve stem is beveled away at 32 to provide a passage between the ends of the valve chamber. Suitable pins 33 are provided for holding the thumb button 27 and valve head 25 upon the valve stem. Access is had to the interior of the valve chamber by unscrewing the

chamber head 34. Conduit 35 is provided for establishing communication between the valve chamber 22 and the cylinder 2. Exhaust port 36 is provided through one wall 5 of the valve chamber and provides communication between one end of the valve chamber and the atmosphere.

In operation, when it is desired to apply a clamp or the like to a cushion seat for holding the cover in place around the border frame, the clamp, such as that shown in my copending application, Serial No. 676,717, which is usually of substantially U-shape, is slipped over the cover and border frame. 15 The clamping tool is applied to the clamp in such a manner that the clamp lies between the bumper plate 12 and the clamping jaw 13, the bumper plate being on the outside of the seat. The thumb button 27 is pushed in and with it the valve stem 24 and valve head 25. The beveled end 28 of the thumb nut will seat upon the edge 29 of the bushing 30 and communication will be established between a suitable source of 20 pressure, not shown, connected to the inlet nipple 23, through the valve chamber 22 and through the conduit 35 to the chamber 2. Pressure will thereby be exerted upon the piston 3, the piston rod will be forced outwardly and through hinge pin 19 force will be exerted upon the clamping jaw 13 so as to force the end 16 thereof into proximity to the lower end of the bumper plate 12. Since the clamp is held between the jaw 35 and the bumper plate it will be bent tightly around the border frame to securely hold the cover in place. With a clamp longer than the jaws of the tool and while the valve is still open, the operator may work 40 the tool from one end to the other of the clamp by using a slight oscillatory motion of the hand, and in this way will be able to cause a more secure clamping action of the clamp upon the cover quickly and conveniently.

After the clamp has been applied and is securely held in place the operator releases thumb button 27 whereupon the coil spring 31 forces the thumb button and valve stem 50 outwardly seating valve head 25 against bushing 26 and thereby cutting off the air under pressure from the cylinder 2. Simultaneously with the shutting off of the air supply the beveled edge 28 of the thumb button is separated from its engagement with bevel 29 by the outward movement of the thumb and communication is established between cylinder 2 and the atmosphere through conduit 35 and the exhaust port 36. 55 The coil spring 8 will force the piston back to its normal position, opening the clamping jaw 13 and the tool is then ready for further use.

While the operation of the clamping tool 65 has been particularly described as applied to

the clamping of cover holding means upon cushion seats, it is quite apparent that by properly shaping the clamping jaw 13 and the bumper plate 12 the tool may be adapted to be used in clamping any other elements 70 desired, such, for instance, as for clamping spring supporting bars or the like around a border frame or the like.

What I claim is:

1. A pneumatic clamping tool comprising 75 a body portion, a piston cylinder and a valve chamber in the body portion, a piston in the cylinder, a manually-operated valve in the chamber, clamping jaws on the body portion, connections between the piston and one of the clamping jaws for operating the latter, a handle on the outside of the body portion, an inlet to the valve chamber for fluid under pressure and conduits for leading the fluid under pressure to one side of the piston. 85

2. A pneumatic clamping tool comprising 90 a body portion, a piston cylinder and a valve chamber in the body portion, a piston in the cylinder, a manually operated valve stem in the chamber having a flattened portion between its ends, a bumper plate attached to one end of the body portion, a clamping jaw pivotally mounted on the bumper plate and connected at one end to the piston, a handle on the opposite end of the body portion, an inlet to the valve chamber for fluid under pressure and conduits for leading the fluid under pressure to one side of the piston. 95

3. A pneumatic clamping tool comprising 100 a body portion, a piston cylinder and a valve chamber in the body portion, a piston in the cylinder, bushings in the valve chamber, a manually operated valve stem in the chamber having a flattened portion between its 105 ends and having valve heads on its ends adapted to alternately seat upon the bushings, a bumper plate attached to one end of the body portion, a clamping jaw pivotally mounted on the bumper plate and connected at one end to the piston, a handle on the 110 opposite end of the body portion, an inlet to the valve chamber for fluid under pressure and conduits for leading the fluid under pressure to one side of the piston.

4. A pneumatic clamping tool comprising 115 a body portion, a piston cylinder and a valve chamber in the body portion, a piston in the cylinder, a manually operated valve stem in the chamber, a bumper plate attached to one end of the body portion having upstanding lugs and a flat anvil surface adjacent the lugs, a clamping jaw pivotally mounted intermediate its ends on the lugs, said jaw having a concave end opposite the anvil surface and connected at the other end to 120 the piston, a handle on the body and an inlet to the valve chamber for fluid under pressure and conduits for leading the fluid under pressure to one side of the piston. 125

5. A pneumatic clamping tool comprising 130

a cylinder, a piston head in the cylinder, a piston rod attached to the piston head and extending through one end of the cylinder, a spring in the cylinder around the rod, a bumper plate attached to the outside of the cylinder, a pivoted clamping jaw connected to the outside end of the rod and arranged to co-act with the bumper plate, a longitudinal valve chamber in the cylinder wall, 10 a manually-operated valve stem in the chamber, an inlet for fluid under pressure at one end of the chamber, an exhaust near the other end of the chamber, a conduit from the chamber to the cylinder located between the inlet and exhaust and a handle attached to the end of the cylinder opposite to the bumper plate end.

6. In a pneumatic clamping tool, a cylinder and piston, a hand grip affixed to one 20 end of said cylinder, a downwardly extending clamping jaw affixed to the other end of said cylinder, means formed as a part of said fixed clamping jaw for pivotally mount-

ing a second clamping jaw intermediate its ends, a piston stem extending through said cylinder and pivotally connected with the upper end of said movable clamping jaw, the lower end of said movable clamping jaw being shaped to coact with said fixed clamping jaw in a clamping operation. 25

7. In a pneumatic clamping tool, a fluid motor comprising a cylinder and piston, and a piston stem extending through one end of said cylinder, a movable jaw pivotally connected at its upper end to the end of said piston stem, a depending fixed jaw affixed to the end of the cylinder and provided with spaced ears between which the movable jaw extends, and means pivotally connecting the movable jaw intermediate its ends with the 30 spaced ears of said fixed jaw whereby it coacts with said fixed jaw in a clamping operation. 35

In testimony whereof, I have hereunto affixed my signature.

CHARLES P. TRIMBLE.
